UNITED STATES PATENT OFFICE.

WILLIAM W. HUELSTER, OF GRAND RAPIDS, MICHIGAN.

DESIGN FOR A HINGE MEMBER.

SPECIFICATION forming part of Design No. 32,900, dated July 3, 1900.

Application filed May 21, 1900. Serial No. 17,481. Term of patent 14 years.

To all whom it may concern:

Be it known that I, WILLIAM W. HUELSTER, a citizen of the United States, residing at Grand Rapids, in the county of Kent and State of Michigan, have invented and produced a new and original Design for a Hinge Member, of which the following is a specification, reference being had to the accompanying drawings, forming a part thereof.

Figure 1 is a perspective of a hinge member for file-boxes, showing my new design; and Fig. 2 is a plan view of the same.

As shown in the drawings, the leading or material feature of my design consists of a flat plate having one end A substantially parallelogram in form and the other end B a prolongation of the said plate, having a segmental outline at one side and the other side prolonged substantially in the line of the edge of the first-named portion of the plate. The portion A of the plate has the upper corner

at one end rounded and is enlarged and prolonged at the other end, the lower outline of the portion A being extended in a right line and having a slight set-off or shoulder D at a ²⁵ distance from the end of the plate corresponding to the axis of the segmental outline of the extension B. Near the extreme end of the plate is a portion C, partially detached and turned outward at right angles to the said ³⁰ plate.

Having thus fully described my invention, what I claim, and desire to secure by Letters Patent, is—

The design for a hinge member, as herein ³⁵ shown and described.

In testimony whereof I affix my signature in presence of two witnesses.

WILLIAM W. HUELSTER.
